UNITED STATES PATENT OFFICE.

CHARLES W. BERGNER, OF ROCHESTER, NEW YORK, ASSIGNOR TO C. T. HAM MANUFACTURING COMPANY, OF ROCHESTER, NEW YORK.

VEHICLE-LAMP.

1,067,965.

Specification of Letters Patent. Patented July 22, 1913.

Application filed October 31, 1912. Serial No. 728,809.

To all whom it may concern:

Be it known that I, CHARLES W. BERGNER, a citizen of the United States, residing at Rochester, in the county of Monroe and

5 State of New York, have invented a new and useful Improvement in Vehicle-Lamps, of which the following is a specification.

This invention relates to that class of vehicle lamps in which the flame chamber 10 opens at the front or rear end, or both, and is provided with a chimney which is surrounded, as well as the flame chamber, by a descending air passage, which receives the air for the support of the flame at the top 15 and conducts the air downwardly to the burner. In lamps of this kind the oil font has usually been inserted into the lamp body from below and secured by fastening devices of various construction. These fastening devices often permit the oil font to 20 drop out of the lamp body and be lost when the fastenings are not properly tightened by negligence or inadvertence or when they have become impaired by use.

25 The object of this invention is to avoid this difficulty by constructing the lamp body with a closed base or bottom portion into which the oil font is inserted through the flame chamber and in which the oil font 30 is securely supported and confined.

In the accompanying drawings: Figure 1 is a vertical cross-section of this improved lamp on line 1-1, Fig. 2. Fig. 2 is a vertical longitudinal section of the lamp on 35 line 2-2, Fig. 1. Fig. 3 is a horizontal section of the lamp on line 3-3, Fig. 1. Fig. 4 is a detached elevation of the oil font and burner. Fig. 5 is a fragmentary side elevation of the lower portion of the lamp 40 body showing the opening therein for the wick raiser shaft. Fig. 6 is a front elevation of the burner cone and parts attached thereto, on an enlarged scale. Fig. 7 is an elevation of the same parts at right angles 45 to Fig. 6. Fig. 8 is a horizontal section of a lamp, on a reduced scale, showing a modified construction of the invention. Fig. 9 is a detached elevation of the oil font and burner of this lamp. Fig. 10 is a detached 50 longitudinal elevation of the burner plate of this modification. Fig. 11 is a front elevation of said plate at right angles to Fig. 10. Fig. 12 is a fragmentary elevation at

right angles to Fig. 9 showing the shield which covers the wick raiser opening. 55

Like reference characters refer to like parts in the several figures.

Referring to the construction of the lamp represented in Figs. 1-7, A represents the main portion of the lamp body which has 60 approximately the form of a horizontal cylinder which is open at the front where it is provided with a door 20 having a glass or lens 21. B represents a lining arranged within this main portion A and spaced 65 therefrom so that an air passage 22 is formed between these parts. This lining operates both as a flame chamber and as a reflector and is preferably of approximately cylindrical form and closed at the rear by a concave reflector 23. A chimney 24 extends upwardly from the lining and is surrounded by an upright cylindrical wall 25 which is open at the top and surmounted by an air injecting flange 26. The air for the support 70 of the flame enters the upper end of the annular passage between the chimney and the surrounding cylindrical wall and passes downwardly through this passage and through the passage between the lining 75 and the body of the lamp in a well known manner. The main portion A of the lamp casing is provided with a closed base C forming a pocket or receptacle for the oil font D into which the latter is inserted from 80 above. For that purpose the lower portion of the lining B is provided with an opening 27 of sufficient size to permit the oil font to be inserted into the bottom pocket or receptacle C and to be removed therefrom. 85 The opening 27 is closed, when the oil font is in position, by a plate 28 which is secured to the burner cone 29 above the skirt 30 thereof having perforations 31. This plate has the same curvature as the lining B 90 and is provided with perforations 32. The burner cone 29 and the cover plate 28 secured thereto surmount the burner which has the usual body 33, wick tube 34, perforated gallery 35 and wick raiser shaft 36. 100 The lamp body is provided in its side with an opening 37 through which the wick raiser shaft projects and which is covered on the inner side of the body by a shield 38 which is secured to the skirt of the burner 105 cone. The air descending through the pas-

sage outside of the lining C supplies the burner by passing through the perforations 31 in the skirt of the burner cone, and part of this air passes directly into the flame 5 chamber through the perforations 32 in the cover plate 28. The latter and the cone secured thereto are held in position by catches 40 which engage against the edge of the lining surrounding the opening 27. The plate 10 is provided at the front with a finger piece 41 for conveniently manipulating the same. In order to place the oil font and burner in position, the front door is opened and the oil font passed through the opening 27 in 15 the lining into the pocket or receptacle C, where the font is seated on the bottom of the pocket. The burner cone and the cover plate secured thereto are then placed in position and secured to the lining. The oil 20 font is in this manner securely attached to the lamp body and prevented from being lost, while special fastenings for the oil pot are rendered unnecessary.

If desired, the cover plate can be separate 25 from the burner cone and the latter mounted on the oil font, as represented in Figs. 8-12. In these figures, 42 represents the burner cone, which is mounted on the oil font, and 43 represents the shield which 30 covers the opening for the wick raiser shaft and which is secured to the oil font. This shield may be provided in its side with a notch 44 for accommodating this shaft. 45 represents the cover plate, which is provided 35 with an opening 46 of sufficient size to clear the burner cone. This plate has at its rear side a shouldered arm 47 which engages in a slot 48 in the lining B and at its front side a catch 49 and finger piece 50.

40 I claim as my invention:

1. In a lamp, the combination of a body having a closed base, a lining in said body forming the flame chamber and having in its lower portion above said base an opening 45 for the insertion of an oil font, an oil font provided with a burner and adapted to be passed through said opening into said base, and means for closing said opening around said burner, substantially as set forth.

50 2. In a lamp, the combination of a body having a closed base, a lining in said body which forms the flame chamber and has in its lower portion above said base an opening 55 for the insertion of an oil font, an oil font adapted to be passed through said opening into said base and provided with a burner, and a cover which closes said opening around said burner, substantially as set forth.

60 3. In a lamp, the combination of a body having a closed base, a lining in said body which forms the flame chamber and is separated from said body by an air passage, 65 said lining being provided above said base

with an opening for the insertion of an oil font, a chimney extending upwardly from said lining, an outer wall surrounding said chimney and separated therefrom by an air passage which leads to the passage between the lining and the body, an oil font adapted to be passed through said opening into said base and provided with a burner, and a cover which closes said opening around said burner, substantially as set forth.

70 4. In a lamp, the combination of a body having a closed base, a lining in said body which forms the flame chamber and has in its lower portion above said base an opening 75 for the insertion of an oil font, an oil font adapted to be passed through said opening into said base and provided with a burner, a cover plate which extends over said opening around the burner, and a burner cone secured to said plate, substantially as set forth.

80 5. In a lamp, the combination of a body having a closed base, a lining in said body which forms the flame chamber and has in its lower portion above said base an opening 85 for the insertion of an oil font, an oil font adapted to be passed through said opening into said base and provided with a burner, and a cover plate which closes said opening around said burner and is provided with catches by which said plate is connected with said lining, substantially as set forth.

90 6. In a lamp, the combination of a body having a closed base, a lining in said body 100 which forms the flame chamber and is separated from said body by an air passage, said lining being provided above said body with an opening for the insertion of an oil font, an oil font adapted to be inserted 105 through said opening into said base, a burner on said font, a burner cone having its skirt provided with perforations and arranged in said air passage between the lining and the body, and a perforated cover plate surrounding the cone above said perforations and covering said opening around the cone, substantially as set forth.

110 7. In a lamp, the combination of a body 115 having a closed base and provided in its side with an opening for a wick raiser shaft, a lining in said body which forms the flame chamber and has in its lower portion above said base an opening for the insertion of an oil font, an oil font adapted 120 to be passed through said opening into said base and provided with a burner having a wick raiser shaft, means for closing said opening in said lining around the burner, 125 and a shield arranged on the inner side of said opening for the wick raiser shaft, substantially as set forth.

8. In a lamp, the combination of a body having a closed base and provided in its side 130

with an opening for a wick raiser shaft, a lining in said body which forms the flame chamber and has in its lower portion above said base an opening for the insertion of 5 an oil font, an oil font adapted to be passed through said opening into said base and provided with a burner having a wick raiser shaft, a plate which covers said opening in the lining around the burner, a burner cone 10 secured to said plate, and a shield secured to said cone and covering said opening for the wick raiser shaft, substantially as set forth.

Witness my hand, this 29th day of October, 1912.

CHARLES W. BERGENER.
